UNITED STATES PATENT OFFICE.

PAUL WEISSBACH, OF GORNAU IM ERZGEBIRGE, GERMANY.

PROCESS OF MAKING STOCKINGS.

Application filed April 21, 1924, Serial No. 707,939, and in France November 23, 1923.

My invention relates to improvements in socks and stockings and a method of manufacturing the same. More particularly the invention relates to a method of knitting 5 socks or stockings having a French heel such as described in U. S. Patent 1,404,702. According to the known method of manufacturing socks or stockings the heel portions were made by widening a plurality of loops on 10 either side of the fabric and narrowing only the marginal loops of the thus formed heel portions necessary to produce the heel rounding. Heel portions made in this manner have the draw-back that they do not properly fit the wearer's heel and the formation 15 of folds cannot be prevented.

It is the object of the invention to overcome this difficulty and provide a method for knitting socks or stockings the French heels 20 of which will be made in a continuous operation and in such a manner that the heel portions will form a real cap and therefore properly fit the heel of the wearer's foot.

In order to more fully explain the improvements provided by my present invention I will now describe the same with reference 25 to the accompanying drawing in which I have illustrated one embodiment of my invention by way of example. Fig. 1 illustrates in a diagrammatical manner a part of a stocking manufactured in accordance with my invention and Fig. 2 shows the same stocking in the finished condition with the edges of the fabric combined by sewing.

30 In carrying my present invention into effect I begin as usual in knitting socks or stockings with the leg of the fabric after finishing of which I allot, by the use of two

covering needle beds which are shifted at each movement through one needle space 40 during the widening operation and by the use of guide stops which are shifted through two needle spaces at alternate movements of the shifting mechanism, a plurality of loops on either side of the fabric for the formation 45 of the heel portions. In continuing the knitting operation the courses of loops are knitted to extend over the whole width of the fabric and the heel portions are formed by continuously transferring the loops disposed within the heel portions a, a' and b, b' and previously allotted to the formation 50 of the latter, laterally to other needles until the required width of the fabric is obtained. At this time the narrowing begins in the portions c, c', d, d' to form the heel cap necessary to obtain the required French heel. When the portions of the heel cap are 55 finished the narrowing is stopped and at the same time a number of needles on either side 60 are cut out so that the further knitting is effected in the width, e, f of the foot portion only.

What I claim is:

The method of manufacturing socks and 65 stockings having French heels consisting in widening the fabric after the leg portion is stopped, stopping the widening of the heel portions at the beginning of the heel cap, narrowing the heel portions until the heel 70 cap is finished, cutting out a number of needles on either side of the fabric and finishing the sock or stocking by knitting in the width of the foot portion.

PAUL WEISSBACH.
